LUMINAIRE

James H. Fahey, Jr., Chicago, Ill., assignor to Joslyn
Mfg. and Supply Co., Chicago, Ill., a corporation of
Illinois

Filed Jan. 5, 1961, Ser. No. 63,451

Term of patent 14 years

(Cl. D48—31)

Fig. 1

Fig. 2

Fig. 3

Fig. 4

Fig. 5

FIG. 1 is a top perspective view of a luminaire, showing my new design;

FIG. 2 is a top plan view of the luminaire;

FIG. 3 is a side elevational view of the luminaire;

FIG. 4 is a bottom plan view of the luminaire, with the broken line showing of the globe element omitted for convenience of illustration; and

FIG. 5 is a front elevational view of the luminaire.

The dominant features of my design reside in the portions, shown in full lines.

I claim:

The ornamental design for a luminaire, substantially as shown and described.
